CLAIM

The ornamental design for an aerosol can body, as shown and described.

DESCRIPTION

FIG. 1 is a side elevational view of an aerosol can body which is a first embodiment of my new design;

FIG. 2 is a top plan view thereof;
FIG. 3 is an bottom plan view thereof;
FIG. 4 is a side elevational view of an aerosol can body which is a second embodiment of my new design;
FIG. 5 is a top plan view thereof;
FIG. 6 is an bottom plan view thereof;
FIG. 7 is a side elevational view of an aerosol can body which is a third embodiment of my new design;
FIG. 8 is a top plan view thereof;
FIG. 9 is an bottom plan view thereof;
FIG. 10 is a side elevational view of an aerosol can body which is a fourth embodiment of my new design;
FIG. 11 is a top plan view thereof;
FIG. 12 is an bottom plan view thereof;
FIG. 13 is a side elevational view of an aerosol can body which is a fifth embodiment of my new design;
FIG. 14 is a top plan view thereof;
FIG. 15 is an bottom plan view thereof;
FIG. 16 is a side elevational view of an aerosol can body which is a sixth embodiment of my new design;
FIG. 17 is a top plan view thereof;
FIG. 18 is an bottom plan view thereof;
FIG. 19 is a side elevational view of an aerosol can body which is a seventh embodiment of my new design;
FIG. 20 is a top plan view thereof;
FIG. 21 is an bottom plan view thereof;
FIG. 22 is a side elevational view of an aerosol can body which is an eighth embodiment of my new design;
FIG. 23 is a top plan view thereof;
FIG. 24 is an bottom plan view thereof;
FIG. 25 is a side elevational view of an aerosol can body which is a ninth embodiment of my new design;
FIG. 26 is a top plan view thereof;
FIG. 27 is an bottom plan view thereof;
FIG. 28 is a side elevational view of an aerosol can body which is a tenth embodiment of my new design;
FIG. 29 is a top plan view thereof;
FIG. 30 is an bottom plan view thereof;
FIG. 31 is a side elevational view of an aerosol can body which is an eleventh embodiment of my new design;
FIG. 32 is a top plan view thereof;
FIG. 33 is an bottom plan view thereof;
FIG. 34 is a side elevational view of an aerosol can body which is a twelfth embodiment of my new design;
FIG. 35 is a top plan view thereof; and,
FIG. 36 is an bottom plan view thereof.
